GARTER AND CLASP THEREFOR

Flora Ellinger, Milwaukee, Wis.

Application June 8, 1932. Serial No. 615,978

2 Claims. (Cl. 24—73)

This invention relates to improvements in garters and clasps therefor, and more particularly to a garter having means at one end portion for detachably depending it from an inner garment, 5 and having clasp means at the other end portion for engagement with the upper portion of a stocking.

In women's apparel it is customary for inner garments such as corsets, girdles and the like to have garters depended therefrom, and in such arrangements the upper ends of the garters are non-detachably secured or sewed to such garments, while the lower ends of the garters are provided with the usual clasps for engaging the hose. This arrangement is open to the objection that the garters are not readily detachable from the garments carrying the same for replacement, repairs or laundering.

It is, therefore, one of the objects of the present invention to provide a ladies' garter having clasp means at one end portion for detachable connection with a supporting garment and having clasp means at the other end portion for detachable connection with hose to be supported by the garter, the elastic or strap portion of the garter being adjustably connected with one of said clasp members whereby the length of the garter may be readily varied.

A further object of the invention is to provide a garter equipped with metallic clasps, which 30 clasps are relatively flat and compact so as not to form objectionable protuberances visible through the outer garments of the wearer and so as not to interfere with the comfort of the 35 wearer.

A further object of the invention is to provide a garter equipped with metallic clasps which are arranged to be covered on one surface by portions of the garter or the garments to which they 40 are attached so as not to contact directly with the flesh of the wearer.

A further object of the invention is to provide a garter equipped with attaching clasps which will firmly engage the apparel to which they are 45 attached, but which will not cause bunching of said apparel, nor will the clasps strain, tear or cause runs in hosiery or the like.

A further object of the invention is to provide a garter consisting of a strip of elastic material 50 carrying substantially duplicate clasps at opposite ends, said clasps being easily manipulated but adapted to firmly but non-damagingly engage fabrics.

A further object of the invention is to provide 55 garters and clasps therefor which are of very

simple construction, are inexpensive to manufacture, are strong and durable, and are well adapted for the purposes set forth.

With the above and other objects in view, the invention consists of the improved garter and 60 clasps therefor, and their parts and combinations as set forth in the claims, and all equivalents thereof.

In the accompanying drawing in which the same reference characters indicate the same 65 parts in all of the views:

Fig. 1 is a front view of the improved garter with the upper clasp shown engaged with a fragment of a garment such as a girdle, and the lower clasp engaged with a stocking;

Fig. 2 is an enlarged front view of the upper clasp of the garter;

Fig. 3 is a side view thereof showing the clasp opened or released and showing in broken lines an intermediate position just prior to the closed 75 or engaging position of the clasp;

Fig. 4 is an enlarged longitudinal sectional view of the upper clasp taken on line 4—4 of Fig. 1;

Fig. 5 is a front view of a slightly modified form 80 of clasp, the clasp being shown in open position; and

Fig. 6 is a longitudinal sectional view of said 85 form of clasp in closed position and applied to a garment.

Referring now more particularly to the drawing, it will appear that a ladies' inner garment such as a girdle or the like, is indicated by the numeral 9, while a stocking is indicated by the numeral 10. The improved garter, designated 90 generally by the numeral 11, is adapted to be interposed between a lower portion of the girdle 9 and an upper portion of the stocking 10, being detachably secured in depending position to the former by an upper clasp 12 and being secured 95 to the latter by a lower clasp 13. Both of the clasps 12 and 13 in all major characteristics are substantially identical and are carried by opposite end portions of an elastic strip 18.

The upper clasp 12 is shown at the upper end 100 portion of the elastic strip in Fig. 1 and in detail in Figs. 2, 3 and 4. Said clasp comprises an inner plate 14, a pivotal frame 15 pivotally connected with the inner plate, and an outer plate 16 pivotally carried by the frame 15. The inner 105 end portion of the inner plate 14 is formed with an integral transverse slotted frame 17 through which the upper end portion of the elastic strip 18 is adapted to extend, and said strip and clasp are adjustable relative to one another, being 110

retained in adjusted position by means of teeth or projections 19 formed on the slotted frame to engage the strip. The other or free end of said inner plate 14 is formed with an inturned hook 20.

The pivotal frame 15 comprises a pair of side arms joined at their outer ends by a transverse bar. The inner ends of said arms are pivotally connected, as at 21, to opposed inturned lugs 22 projecting from a face of the inner plate 14.

The outer plate 16 corresponds in general in shape and proportions to the inner plate, and said outer plate, inwardly of the upper end thereof, is pivotally attached to the transverse bar portion of the frame 15, said pivotal connections being indicated by the numerals 23. The lower edge of said plate 16 is formed with a projecting lip 24 to be engaged by a finger-nail for purposes of manipulating the clasp, while the opposite or upper end of the plate 16 is provided with an inwardly angled tongue 25 to engage in the hook 20 of the inner plate when the clasp is closed.

The upper clasp member of the improved garter is for the purpose of readily detachably securing the garter to a ladies' inner garment, such as a girdle, to permit the garter to depend therefrom. To engage the clasp with the garment 9, said clasp is first opened relatively fully, as shown in full lines in Fig. 3, and then the lower edge portion of the garment is extended so as to overlap the inner plate 14 of the clasp. Next, the outer plate is moved upwardly, inwardly through the position shown in broken lines to ultimately engage the tongue 25 under the hook 20 and thereby clampingly confine the portion of the garment between portions of the inner plate and the pivotal frame and outer plate. The pivotal frame, with its pivotal connections with the plates 14 and 16, permits these movements and in the closed position illustrated in Figs. 1 and 4, the outer plate occupies a flat, compact position relative to the other parts and stays in this position against undesired dislodgment due to the fact that the pivotal frame serves as a toggle and the pivotal connections are on opposite sides of the longitudinal center line.

It is to be noted that the free upper end portion of the elastic strip 18 of the garter is extended on the inner surface of the garment 9 so that the clasp is actually confined between the strip 18 and garment 9, whereby the flesh of the wearer is protected against direct contact with the metallic clasp. As before noted, adjustments to lengthen or shorten the garter are easily accomplished either with the upper clasp free, or in its engaged position.

The lower clasp member, designated generally by the numeral 13, is practically identical in construction with the upper clasp member except that it is directed in the opposite direction, and the upper end portion of the lower plate thereof is formed with apertured ears 26 through which the lower plate is sewed to the lower end portion of the elastic strip 18, as at 27.

For the purpose of supporting a stocking, the lower clasp member is engaged with the upper portion of the stocking 10, as shown in Fig. 1, and the clasping engagement and manipulation of said lower clasp member is the same as that described in connection with the upper clasp member. Both clasp members in engaged closed positions are very flat and compact and do not form objectionable protuberances. Also, the clasps engage the garments without any material bunching, and in the case of a hose no undue strain is imposed thereon, and it is not damaging to the sheerest type of hosiery.

In Figs. 5 and 6, a slightly modified type of clasp is illustrated which is applicable to either end portion of the garter elastic strip, or to both end portions. The clasp illustrated is intended for the upper portion of the strip because of the integral slotted bar portion 17', but the inner plate 14' may be modified to eliminate said bar to be provided with ears like those at 26 in Fig. 1 for sewed attachment to the elastic strip. The difference in said modified form of clasp lies in the free end of the inner plate 14' which is raised and slotted as at 20', and into said slotted portion 100 the tongue 25' of the outer plate 16' is adapted to extend.

While the improved form of clasp is especially suitable for garters and the like, it should be understood that it may have, within the scope of the invention, a more general application, as it may be used wherever a compact and effective type of clasp is required in connection with garments, apparel and elsewhere.

From the foregoing description it will appear 110 that the improved garter and clasps therefor are simple and novel, and are well adapted for the purposes set forth.

What is claimed as the invention is:

1. A clasp, comprising a base plate having an angled catch portion, and toggle means secured to said base plate remote from the catch portion and having an inwardly angled tongue, a substantial surface portion of the tongue being releasably engageable with an area of said catch portion in a superimposed position of the toggle means with respect to the base plate, the contacting surfaces of the tongue and the catch being flat and of relatively large area, whereby a piece of flexible material may be clamped between said contacting surface portions of said tongue and catch.

2. A clasp, comprising a base plate having a catch portion, and toggle means secured to said base plate remote from the catch portion and having an inwardly angled tongue releasably engageable with said catch portion whereby a piece of flexible material may be clamped between surfaces of said tongue and catch portions, said clamping surfaces of the tongue and catch portions being flat and of relatively large area, said base plate having an integral serrated loop portion whereby a strap may be releasably secured through said loop portion.

FLORA ELLINGER. 140
